(57) **CLAIM**

The ornamental design for a swimming pool cleaner, as shown and described.

DESCRIPTION

FIG. 1 is a first perspective view of the first element of a swimming pool cleaner, showing my new design;

FIG. 2 is a second perspective view of the first element thereof;

FIG. 3 is a front elevational view of the first element thereof;

FIG. 4 is a rear elevational view of the first element thereof;

FIG. 5 is a left side view of the first element thereof;

FIG. 6 is a right side view of the first element thereof;

FIG. 7 is a top plan view of the first element thereof;

FIG. 8 is a bottom plan view of the first element thereof;

FIG. 9 is an exploded view of the first element thereof;

FIG. 10 is an enlarged view of the selected portion 10 in FIG. 2;

FIG. 11 is a first perspective view of the second element of the swimming pool cleaner;

FIG. 12 is a second perspective view of the second element thereof;

FIG. 13 is a front elevational view of the second element thereof;

FIG. 14 is a rear elevational view of the second element thereof;

FIG. 15 is a left side view of the second element thereof;

FIG. 16 is a right side view of the second element thereof;

FIG. 17 is a top plan view of the second element thereof;

FIG. 18 is a bottom plan view of the second element thereof;

FIG. 19 is a perspective view of another state of the second element thereof;

FIG. 20 is a first combination view of the first element and the second element of the swimming pool cleaner;

FIG. 21 is a second combination view of the first element and the second element thereof; and,

FIG. 22 is an exploded view of the swimming pool cleaner.

(Continued)

The broken lines shown in the drawings depict portions of the swimming pool cleaner that form no part of the claimed design. The dash-dot lines illustrate the boundary of the enlarged views and form no part of the claimed design.
